UNITED STATES PATENT OFFICE.

AGNES O. YOUNGS, OF BOZEMAN, MONTANA.

EXTENSION FLY-SWATTER.

1,263,988.

Specification of Letters Patent. Patented Apr. 23, 1918.

Application filed November 10, 1916. Serial No. 130,584.

To all whom it may concern:

Be it known that I, AGNES O. YOUNGS, a citizen of the United States, residing at Bozeman, in the county of Gallatin and 5 State of Montana, have invented certain new and useful Improvements in Extension Fly-Swatters; and I do hereby declare the following to be a full, clear, and exact description of the invention, such as will enable 10 others skilled in the art to which it appertains to make and use the same.

This invention relates to improvements in fly swatters having an extensible handle.

The object of this invention is to provide 15 an efficient fly swatting device which may be readily and quickly assembled and the killing of the flies by swatting them with the device assured.

A further object of this invention is to 20 provide a handle having a T-shaped head to which is secured a rectangular piece of reticulated material and is so secured to the head that any fear of the same breaking at its point of connection is eliminated.

25 A further object of this invention is to provide a handle having a plurality of sections which telescope into one another when making the handle long or short as desired.

A still further object of this invention is 30 to provide a fly swatting device comprising a handle having a T-shaped head to which is secured a rectangular piece of reticulated material and provided with a loop through which extensible handle sections are placed 35 when not in use and a cup for holding the lower ends of the sections together and against separation.

A further object of the invention is to 40 provide a device of this character which will be simple, practical and comparatively inexpensive in construction and one that can be manufactured and sold at a comparatively low cost.

45 With these and other objects in view the invention consists in the novel combination and arrangement of parts hereinafter more fully set forth and defined in the claim hereto appended.

In the drawing—

50 Figure 1 is a plan view of my improved extensible fly swatter as made in accordance with this invention having parts in section to more fully illustrate the details of construction.

Fig. 2 is an edge of the same with parts 55 in section.

Fig. 3 is a sectional view taken on the line 3—3 of Fig. 2, and

Fig. 4 is a sectional view taken on the line 4—4 of Fig. 2. 60

Like numerals of reference designate like and corresponding parts in all the figures of the drawing.

Referring more particularly to the drawing the numeral 1 designates the handle which is formed of wood or any other suitable material and is preferably circular in cross section and comprises a T-headed cross bar 2 which is formed at one end of the handle 1. The T-headed cross bar 2 is substantially rectangular in shape and the purpose of which will be hereinafter more fully set forth. 65

A sheet of reticulated material 3 substantially rectangular in shape is bent at its medial portion as at 4 to provide the two sections 5 and 6 which are adapted to lie in parallel relation and have their ends secured to the head 2 by fasteners 7 which fasteners extend through the reticulated material and the head 2 and are clenched or otherwise bent therearound to prevent the displacement of the reticulated material from the head 2. The ends of the reticulated material completely cover the head and have 70 facial engagement on opposite sides thereof to reinforce the reticulated material and obviate any fear of the same breaking at its point of connection with the head due to 75 the bending of the same when swatting flies or other insects. 80

The handle member 1 comprises a plurality of sections 8 and 9 which sections are substantially cylindrical in cross section and 85 has secured to one end by rivets 10 or other suitable fastening means the cups 11 which cups extend beyond the ends of their respective sections and are adapted to receive the ends of the adjacent section therein for 90 making the handle 1 long or short as desired. 100

The cups 11 are formed of tin or other suitable metal suitable for purpose and frictionally engage the ends of the adjacent sections of the handle to hold the same therein and prevent the accidental displacement of the same in the use of the device. 105

A loop 12 of wire or other suitable mate-

rial, substantially U-shaped has the ends of its arms bent angularly and secured to the handle 1 near the head 2 and adapted to receive the ends of the handles 8 and 9 therein when disconnected from their respective sections when not in use and a cup 13 formed of suitable metal or other material is adapted to be arranged on the ends of the handles when in the disconnected position to hold the handles in the loop 12 and against displacement when the device is not in use.

The loop 12 is provided with the annularly bent ends 14 which ends are secured in the handle portion 1 at diametrically opposite points in grooves 15 and permit the other sections of the handles 8 and 9 to be placed therein when the device is in an inoperative position.

In operation, the handle section 8 is slipped upon the handle 1 and is held thereon by the cup 11. The handle 9 is placed on the end of the handle 8 through the cup 11 and is held against displacement by the frictional engagement of the cups 11 with their respective handles.

It can be readily seen that the device may have the handle of any desired length as required.

Copies of this patent may be obtained for five cents each, by addressing the "Commissioner of Patents, Washington, D. C."

What is claimed is:—

An extension fly swatter comprising handle sections consisting of end sections, and an intermediate section, a head formed integrally with one end of one end section, a retaining cup secured to one end of the other end section, and to one end of the intermediate section, said cup on the intermediate section adapted to be fitted over the free end of the head carrying section, the cup on one end of the other end section adapted to be fitted upon the free end of the intermediate section, a reticulated fabric secured to the opposing faces of the head carrying section, a retaining loop secured to the head carrying section and a retaining cup adapted to be fitted over the free ends of the sections when collapsed retaining the intermediate and other end section into the loop and upon the head carrying section, as and for the purpose specified.

In testimony whereof I affix my signature in presence of two witnesses.

AGNES O. YOUNGS.
